UNITED STATES PATENT OFFICE.

ARTHUR LATTINVILLE, OF HAMILTON, ONTARIO, CANADA

SHOE-LACE.

1,125,858.

Specification of Letters Patent. Patented Jan. 19, 1915.

Application filed April 10, 1914. Serial No. 830,965.

To all whom it may concern:

Be it known that I, ARTHUR LATTINVILLE, a subject of the King of Great Britain, and a citizen of the Dominion of Canada, residing at 187 Queen street north, in the city of Hamilton, in the county of Wentworth, Province of Ontario, Dominion of Canada, have invented certain new and useful Improvements in Shoe-Laces, of which the following is a specification.

This invention relates to shoe laces and it has more particular reference to that type of lace embodying a flexible portion or having at one end thereof an enlarged shield, said shield serving to retain one end of the lace in position.

The object of my invention is to provide a new or improved type of lace of the nature specified, and to this end my invention consists essentially in securely attaching the lace to the button or shield member in single file.

The accompanying drawing is in illustration of my invention, Figure 1, being a perspective view of a boot having my improved lace laced thereto; and Fig. 2, is a detail of the lace end hereinafter more particularly referred to. Fig. 3 is an enlarged detail of the button end of the lace.

According to my present invention the

lace 1, is provided at one end with a button 2, having slots 3, 3, formed therein. The lace 1, is threaded therethrough the said slots 3, 3, and stamped or otherwise flattened down so that the tongues 4, 4, are forced to 35 impinge in the fabric of the lace 1.

In use, the lace 1, is threaded through the eyelet 5, with the button 2, on the inside of the boot or shoe, and laced as shown up to the hooks 6, 6. The free end of the lace 1, is 40 then placed at the back of the boot as shown and the lace laced over the hooks 6, 6, whereupon the loose end of the lace is drawn tight and the shoe presents a neat and finished lacing.

Having thus described my invention, what I claim as new and desire to secure by Letters Patent, is:—

A shoe lace comprising a flexible member, and a button at one end thereof having slots 50 and tongues therein, said flexible member being threaded through said slots and the tongues forced into engagement therewith, as set forth for the purpose specified.

In witness whereof I have hereunto set my 55 hand in the presence of two witnesses.

ARTHUR LATTINVILLE.

Witnesses:

GERTIE NICHOLSON,
ALFRED T. BRATTON.
